UNITED STATES PATENT OFFICE.

ETHAN I. DODDS, OF PITTSBURGH, PENNSYLVANIA, AND ROBERT S. FERGUSON, OF WASHINGTON, DISTRICT OF COLUMBIA, ASSIGNEES TO FLANNERY BOLT COMPANY, OF PITTSBURGH, PENNSYLVANIA.

ILLUMINATING DEVICE.

1,275,871.

Specification of Letters Patent. Patented Aug. 13, 1918.

Application filed July 25, 1917. Serial No. 182,732.

To all whom it may concern:

Be it known that we, ETHAN I. DODDS, a citizen of the United States, residing at Pittsburgh, in the county of Allegheny and State of Pennsylvania, and ROBERT S. FERGUSON, a citizen of the United States, residing at Washington, District of Columbia, have invented certain new and useful Improvements in Illuminating Devices; and we do hereby declare the following to be a full, clear, and exact description of the invention, such as will enable others skilled in the art to which it appertains to make and use the same.

This invention relates to improvements in illuminating devices, and more particularly to lamps,—the object of the invention being to so construct a lamp that it may be rendered luminous by means of artificial light supplied therein at intervals and for brief periods of time, and so that it will retain and emit light for a considerable period after the actuating or energizing light shall have been extinguished, whereby a mild, cold light may be provided at a minimum cost, sufficient in brilliance for ordinary purposes where a mild light is desired.

A further object is to provide simple and efficient supporting means for illuminating material within a globe and in a manner to insure the uniform activating or energizing of said material by a source of light contained within the supporting means.

With these and other objects in view, the invention consists in certain novel features of construction as hereinafter set forth and pointed out in the claims.

In the accompanying drawings; Figure 1 is a view of a lamp embodying our improvements, and Fig. 2 is a view of a modification.

1 represents a globe having a flanged mouth portion 2 which may be received by the flanged base portion 3 of a lamp fixture such as commonly employed in incandescent lamp installation. The socket of the lamp fixture receives the base member 4 of an incandescent lamp bulb 5 so that the latter will be disposed within the globe 1, or rather within a cage or carrier 6, located within the globe.

The cage or carrier 6 is constructed of netting (preferably wire netting) of comparatively close mesh and supports a material 7 which will absorb light so as to become luminous when exposed to a source of light. Such phosphorescent material may comprise zinc or calcium sulfid and will preferably also contain an infinitesimal amount of radioactive material, such as a salt of radium. This material is supported in place in the interstices of the mesh of the cage and is properly distributed throughout the latter. A material 8 is located in the bottom of the cage or carrier and this material may be of the same composition as that above described, except that it will contain a sufficiently greater proportion of radioactive material (such as a salt of radium) as will render this body or mass 8 of material permanently luminous.

The upper open end of the cage or carrier 6 enters the flanged mouth portion 2 of the globe 1 and may be held in place by the flanged edge 9 of a disk or closure 10,—the latter having an opening for the accommodation of the lamp base 4 and an annular flanged portion 11 which closely embraces said lamp base. The disk 10 thus serves to hold the cage 6 in place and also to cover the cage and mouth of the globe and thus preclude the entrance of dust, moisture or other foreign matter.

Instead of making the cage or holder of wire or other netting, we may employ such material as mica in the construction of said cage, as illustrated at 12 in Fig. 2.

With our improved lamp, the material supported by the cage 6 may be activated or energized so as to render the same sufficiently luminous for ordinary purposes where a mild light is desired, by light from the incandescent lamp 5,—for which purpose, the lamp 5 may be lit for brief periods of time at intervals,—the light absorbing material remaining luminous for a considerable period after the lamp 5 has been extinguished.

The permanently luminous material 8 in the bottom of the cage will serve not only as a permanent spot light but it will also act to mildly excite or activate the material 6 and cause the same to glow somewhat even

when it has not been reactivated for a long period by the temporary lighting of the incandescent lamp 5.

Having fully described our invention, 5 what we claim as new and desire to secure by Letters-Patent, is:—

1. An illuminating device, comprising a globe, a carrier supported therein, phosphorescent material carried by the upright 10 wall of said carrier and permanently luminous material supported by the bottom of said carrier.

2. An illuminating device, comprising a globe, a cage inclosed by and supported 15 therein, phosphorescent material supported by the wall of said inclosed cage, and a source of light within the cage.

3. An illuminating device, comprising a globe, a cage constructed of meshing supported within said globe, phosphorescent ma- 20

terial supported in the interstices of the meshing of said cage, and a source of light within said cage.

4. The combination of a globe having a mouth portion, a meshed cage supported 25 within the globe, an electric lamp entering the cage, phosphorescent material supported in the interstices of said meshed cage, and a disk for supporting said cage and constituting a closure for the same and the globe 30 around the base member of the electric lamp.

In testimony whereof, we have signed this specification in the presence of two subscribing witnesses.

ETHAN I. DODDS.
ROBERT S. FERGUSON.
